DESIGN FOR A FUR COLLAR

Mario Frascino, New York, N. Y.

Application August 12, 1941, Serial No. 102,801

Term of patent 3½ years

To all whom it may concern:

Be it known that I, Mario Frascino, a citizen of the United States of America, residing in New York city, county of New York, and State of New York, have invented a new, original, and ornamental Design for a Fur Collar, of which the following is a specification, reference being had to the accompanying drawing, forming part thereof, wherein,

I claim:

The ornamental design for a fur collar, substantially as shown.

MARIO FRASCINO.
